UNITED STATES PATENT OFFICE.

CALEB H. GRIFFIN, OF BOSTON, MASSACHUSETTS.

DRESS-FORM.

SPECIFICATION forming part of Letters Patent No. 365,302, dated June 21, 1887.

Application filed June 12, 1886. Serial No. 205,027. (No model.)

To all whom it may concern:

Be it known that I, CALEB H. GRIFFIN, of the city of Boston, in the county of Suffolk and State of Massachusetts, have invented an Improvement in Dress-Forms, of which the following is a full, clear, and exact description.

The object of my invention is to provide a cheap, simple, convenient, and durable form for suspending dress-skirts and dress-waists or dresses and other garments being draped, trimmed, and fitted, and for exhibiting dresses and other similar garments for sale, as well as to retain dresses upon when not being worn, so as to prevent jamming or wrinkling the same; and it consists in the construction, combination, and arrangement of the several parts of the form, as hereinafter more fully described, and specifically set forth in the claim.

Figure 1 represents a perspective view of a dress-form constructed according to my invention. Fig. 2 represents a similar view of the same in an expanded position. Fig. 3 represents an elevation of a portion of the actuating mechanism removed. Fig. 4 represents a plan of a detached portion.

A represents the legs or base, which supports the central vertical tube, B, within which the vertical adjustable tube or rod C is secured and held at the desired elevation by means of the set-screw D, the upper end of the said tube B passing through the top operating-knob, W, as shown, said knob being provided with a spring-catch, V, which engages with the notches in the top portion of the tube C, as shown in Fig. 2, so as to hold the adjustable wire skirt-frame E and waist or bust portion F in position, as desired for use. For convenience, the skirt-frame E and waist-form F are constructed in four adjustable longitudinal sections, connected together at the top by screws entering the support-disk G, as shown, and at the bottom by the pivoted short folding connecting-bars H, which permit the skirt-sections E to be adjusted and expanded circumferentially by simply forcing downward the said knob W, which is attached to the sleeve I; and to this sleeve I are secured the upper ends of the four actuating incline or oblique rods J, which slide through holes or eyes formed in the inward ends of the horizontal guide-rods K, the outward ends of which are secured to the interior

lower end portions of the said waist-form F, one being provided for each section. These oblique rods J are bent inwardly at the terminus of the incline portions, and are secured to the short sleeve M by solder or in any suitable manner, and are then extended outward therefrom at about a right angle, so as to form actuating-inclines L, which pass through holes or eyes formed in the inward ends of the lower set of horizontal guide-rods, N, the outward ends of which are secured to the horizontal segmental wire-frame portions O, as represented. The said actuating incline rods L are formed more obliquely than the upper inclines, J, so as to permit the bottom of the skirt-form E to be expanded more than the waist-form F, which, being secured at its extreme upper end, remains in the same position at all times, while the whole form is expanded, increasing gradually downward to the bottom thereof; but, if desirable, it may be constructed to expand at the top as well. The actuating incline rods L are bent inward until they come in contact with the short sleeve P, to which they are connected by solder, or otherwise, so that the three sleeves I M P may be slid up and down upon the center vertical rod or tube, C, freely in adjusting the skirt-form, as shown and described.

To the upper portion of the rod or vertical tube C is permanently secured the support-bracket R, having four radiating or horizontally-projecting short arms or ears provided with holes, through which the stay-rods S pass at their upper ends, and extend obliquely downward and outward, and are connected at their ends with the said segmental sections O loosely, so as to allow the sections of the dress-form or wire frame composing the same to be supported in position thereby and expanded or contracted, as desired.

The form or dress-form frame may be elevated or adjusted vertically by means of the collar T, provided upon the lower portion of the vertical rod C, and resting on the upper end of the vertical tube B and secured temporarily upon said rod C at the desired point by a set-screw, V, and thereby permit the said form to be turned around or rotated, when desired, by releasing the lower set-screw, D, which passes through the said tube B and has a bearing against the rod C. The other portions of the

frame, consisting of the wire braces, horizontal and vertical stays, being of usual construction, are not fully or more particularly described, as they form no essential feature of my present invention.

Having thus described my invention, what I claim is—

The combination, with the adjustable skirt-frame E and waist-form F, of the oblique actu-

ating rods J, guide-rods K, oblique actuating rods L, guide-rods N, sliding sleeves I M P, adjustable tubes B C, support-bracket R, and stay-rods S, adapted to adjust the segmental sections of the said frame E F, as described.

CALEB H. GRIFFIN.
